UNITED STATES PATENT OFFICE.

NICHOLAS RATCHFORD AND LEWIS D. EVANS, OF PLAIN CITY, OHIO.

RAILWAY-FROG.

SPECIFICATION forming part of Letters Patent No. 484,525, dated August 19, 1890.

Application filed August 17, 1889. Serial No. 321,128. (No model.)

To all whom it may concern:

Be it known that we, NICHOLAS RATCHFORD and LEWIS D. EVANS, citizens of the United States, residing at Plain City, in the county 5 of Madison and State of Ohio, have invented a certain new and useful Improvement in Railway-Frogs, of which the following is a specification.

Our invention relates to railway-frogs; and 10 the objects of our invention are to provide railways with a superior form of frog so constructed as to admit of its use in connection with ordinary forms of main and side tracking, to prevent unnecessary wear on the frog 15 by so constructing the frog as to prevent cars which are passing over the main track from running upon the frog-rail, to provide the frog-plate with a rail-section which will be automatically shifted across the main-track 20 rail when the frog is in use, to admit of its use in connection with continuous main-track rails, to so construct the same as to prevent 25 its operation being impaired by snow or ice, and to construct the same in a strong and durable manner. These objects we accomplish in the manner illustrated in the accompanying drawings, in which—

Figure 1 is a perspective view of our improved frog shown in connection with the 30 main track. Fig. 2 is a plan view of the frog shifting-rail section and frog-plate, showing a portion of the main-track and guard rail. Fig. 3 is a plan view in detail of a portion of the side-track guard-rail, the shifting-rail rod, 35 and its spring, with the outer side-track rail and intervening trip-rail removed. Fig. 4 is a sectional view taken on line $x-x$ of Fig. 3. Fig. 5 is an inner side elevation of the outer rail of the side track, showing the trip-rail 40 connected therewith. Fig. 6 is a vertical transverse section taken on line $y-y$ of Fig. 2, and Fig. 7 is a sectional view taken on line $z-z$ of Fig. 5.

Similar letters refer to similar parts throughout the several views.

a and a' represent, respectively, the outer and inner rails of the main track.

b represents an oblong frog-plate, the base of which is secured to the ties in such manner as to bring its body parallel with and against the outer side of the main-track rail a' . The upper surface of the body of the

frog-plate is, as shown, flush with the upper surfaces of the main-track rails. c represents a bar or section of rail of a width corresponding with that of the upper portion of the track-rail. This rail-section c , as shown, rests upon the upper side of the frog-plate adjoining the outer side thereof and a short distance from the main-track rail a' . The rear end of this 55 shifting rail is thickened downwardly and has projecting outwardly from said thickened portion a lug c' , which is seated loosely within a suitable recess or depression formed in the upper side of the outwardly-projecting 60 rear portion of the frog-plate. The lug c' of the shifting rail is pivoted in this position by means of a short pin or bolt d made to pass through a vertical bolt-hole formed in the outwardly-projecting rear portion of the frog- 65 plate, said bolt-hole being of slightly-greater 70 circumference than the bolt or pin d .

Coiled about that portion of the bolt d which is within the frog-plate b is a spring e , having its lower end rigidly secured to the 75 frog-plate and having its upper end projecting upwardly through the bolt-hole of the lug c' and bent outwardly into a short groove formed in the upper surface of said lug. A nut f , screwed upon the upper projecting end 80 of the bolt d , operates to hold the shifting-rail lug against the frog-plate. The tension of the spring e is such as to normally hold the shifting rail away from and parallel with the main-track rail a' . The forward end of the 85 shifting rail is, as shown, beveled outwardly to a half-wedge shape.

g represents the inner side-track rail, which approaches the forward end of the frog-plate from a switch in a diagonal line between the 90 two main-track rails. When at a point opposite the forward beveled end of the shifting rail, the side-track rail g is bent in a line parallel with the main-track rail and terminates a short distance from said bend. As it 95 approaches the main-track rail and frog-plate, the inner side-track rail g is gradually elevated by blocks placed upon the ties until that portion thereof which is opposite the shifting rail is of a height corresponding with 100 said shifting rail. A rail g' , having its end in close proximity to the rear end of the shifting rail c , is made to run outwardly at a slight angle with the main-track rail a' and forms,

as hereinafter described, a straight continuation of the diagonal portion of the rail g . This rail g' has its end blocked up to a height corresponding with the rails c and g and 5 gradually inclines downwardly therefrom.

- h represents the outer side-track rail, which runs parallel with the inner rails g g' . Running parallel with the side rail h and on the inner side thereof is a guard-rail section i .
- 10 k represents a trip-rail, formed of two metallic plates or bars, having their adjoining ends jointedly connected at k' , as shown. The upper half of this trip-rail is of but slight thickness, while its lower half is thickened to 15 correspond with the space between the upper sides of the rails h and i . The ends of the trip-rail k are pivotally connected with the inner side of the side rail h in such position as to bring the center of the length of said 20 trip-rail transversely opposite the shifting rail c . The pivot bolt or pin which connects one end of the trip-rail with the rail h is pivoted within a slot h' , formed in the end of the trip-rail, thus admitting of the central portion 25 of the trip-rail being lowered, as hereinafter described.

As shown in Fig. 4 of the drawings, the under side of the trip-rail at about the center of its length is made to bear upon a lug or 30 head m , projecting upwardly between the lower portions of the rails i and h from the outer end of the upper arm of a bell-crank lever l . This lever l is pivoted at a point beneath the lower flange of the rail i between 35 two parallel transverse arms n , which are supported, as shown, between the ties by a cross-arm n' .

Jointedly connected with a lug r , projecting from the under side of the shifting rail c 40 at a point below its top flange, is a lever-rod o , which extends outwardly and thence downwardly, and again outwardly to a point beneath the rails i and h and beneath the bell-crank l . The lower arm m' of the bell-crank 45 is pivoted within a slot formed in the rear and slightly-enlarged portion of the rod o . An outward continuation o' of the rod o from the outer end of its enlarged slotted portion is made to pass loosely through a slot formed 50 in the lower portion of a plate n^2 , which extends downwardly from the outer edge of the cross-plate n' . This continuation of the rod o is provided on its outer end with a fixed nut or head o^2 and with a washer p , adjoining 55 the outer side of the plate n^2 . Coiled about this rod-continuation and bearing between the washer p and head o^2 is a spring q . The tension of this spring q is such as to normally hold the lug m of the bell-crank elevated, as 60 shown in Fig. 4 of the drawings, sufficiently to support the upper portion of the trip-rail above the upper surfaces of the rails h and i . That portion of the rails h and i opposite the shifting rail c and the elevated portions of 65 the rails g and g' are blocked up to a height corresponding therewith.

In order to fully understand the operation

and advantages of our improved frog, we will suppose that a train is running upon the main track. It being desired to side-track the cars, 70 the engine and cars are disconnected and the cars directed by a switch in the usual manner on the side-track rails g and h after the passing of said switch by the engine. Owing to the fact that the frog-rail c is not in connection with the main track a' , and that the latter is continuous, it will be seen that the engine will travel up the main track past the frog-rail without running upon or coming in contact with the frog-rail. The detached cars 80 which have been switched upon the side track advance upon the rails g and h until the outer wheels of the cars run upon and press downward the trip-rail k . This trip-rail is so seated upon the bell-crank lug m that the pressure 85 thus caused upon said trip-rail will operate to trip said bell-crank lever sufficiently to throw inward the rod o with which it is connected. This inward movement of the rod o will, through its connection with the shifting 90 rail c , operate to drive the forward beveled end of the latter into line with the rail g at that point where it is bent in a parallel line with the main track.

A depression or cross-channel r' is formed 95 in the upper side of the frog-plate opposite the point of connection of the shifting rail and rod o to allow free inward movement of the shifting-rail lug r . In executing this movement the rear end of the shifting rail 100 turns on its pivot-bolt, while its forward portion slides over the upper side of the frog-plate, and the rail a' thus forming a complete crossing of the latter and producing an intervening continuation of the rails g and g' , as 105 shown in dotted lines in Fig. 2 of the drawings. The compression of the spring q between the washer p and rod-head o^2 caused by the above-described movement of the rod o will place said spring under sufficient tension to again draw outward the rod o and rail c when the trip-rail has been released from the weight of the cars, and said trip-rail will 110 again resume its normal position. The forward end of the frog-plate b is, as shown, provided with a downwardly and forwardly beveled guard-head of the height of the shifting rail, which will prevent the forward end of the shifting rail from becoming engaged with a chain or other car attachment which may 115 be depending from the cars. The rail c in turning to meet the rail g will cause the coiled spring e , through the movement of the pivot-bolt d , to be placed under such tension that in case the spring q should become disabled 120 the spring e will be sufficient to withdraw the rail c to its normal position after the passing of the cars. It will be seen that the upper side of the frog-plate is of such width as to 125 meet the main-track rail, and thus prevent the entrance of snow and ice between said plate and rail. The passage of the engine or car wheels over the main-track rail a' will 130 operate through the flanges of said wheels to

press downward or remove the snow which may have accumulated between the parallel portion of the rail *g* and main-track rail, and thus prevent any obstruction of the free movement of the shifting rail and allowing it to make a perfect connection with the side-track rail.

Although the form of spring mechanism herein shown for the purpose of withdrawing the shifting rail to its normal position is preferable, it is obvious that other forms might be used to accomplish this purpose. It is also obvious that the particular shapes of castings and parts herein shown and described may be altered without affecting the principle of our invention.

By the herein-described construction and operation it will be seen that when the frog is in use a complete bridging or crossing of the main-track rail is effected, which will thereby prevent the unnecessary use and wear upon the main-track rail. It will also be seen that when the main track is in use the frog-rail is thrown completely to one side, and is not, as is usual, worn by the traveling thereon of cars upon the main track.

Our improved frog and its operating mechanism may be connected with the main track of a railway at any desired point without the necessity of removing or altering the main-track rails.

Having now fully described our invention, what we claim, and desire to secure by Letters Patent, is—

1. The combination, with the continuous main-track rails *a* and *a'*, the side-track rails, and a fixed frog base plate adjacent to and of the height of said main-track rails, of a shifting-rail section *c*, pivoted upon said frog-plate, and a spring *e*, coiled and supported, as described, about said shifting-rail pivot-bolt, said shifting rail being adapted to be pressed across the inner main-track rail into line with the inner side-track rail, substantially as described.

2. The combination, with the main and side track rails, a fixed frog or base plate adjacent to and of the height of said main-track rails, and the spring-actuated shifting rail *c*, pivoted upon said frog-plate, of the hinged and slotted trip-rail *k*, pivoted, as described, to the inner side of the outer side-track rail, the guard-

rail *i*, bell-crank lever *l*, pivoted between two arms *n*, supported beneath rails *h* and *i* and supporting, as described, the trip-rail *k*, and a spring-actuated rod *o*, jointedly connecting said shifting rail *c* and lower bell-crank arm *m'*, substantially as and for the purpose set forth.

3. The combination, with the main and side track rails *a* and *a'*, fixed frog-plate *b*, adjacent to and of the height of the main-track rails, and the shifting rail *c*, pivoted, as described, upon said frog-plate, of the hinged and slotted trip-rail *k*, pivoted, as described, to the inner side of the outer side-track rail, the side-track guide-rail *i*, bell-crank lever *l*, pivoted between two frame-arms *n*, supported beneath rails *h* and *i* and supporting, as described, the trip-rail *k*, rod *o*, jointedly connecting shifting rail *c* and lower bell-crank arm *m'*, a vertical frame-piece *n*, depending from a cross-arm *n'* extending between two ties, said frame-piece *n* having a slot in its lower end through which passes an outer continuation of the rod *o*, a washer *p* on said rod-continuation and bearing against frame-piece *n*, and a coiled spring *q*, surrounding said rod-continuation between the washer *p*, and a nut or enlargement *o'* upon the outer end of said rod, substantially as and for the purpose specified.

4. The combination, with the continuous main-track rails *a* and *a'* of a fixed frog-plate on base *b*, adjacent to and of the height of said rail *a'*, of the shifting-rail section *c*, pivoted upon said frog-plate and adapted to be automatically pressed across said rail *a'* into line with the inner side-track rail when a car is passing upon the side track over the frog and to be automatically returned to its place so as to leave the main-track rail *a'* clear after the car has passed off from the frog, and the side-track rails *g* *g*, so elevated at the points of intersection with the shifting-rail section *c* as to form a continuous line horizontally as well as vertically with said shifting-rail section.

NICHOLAS RATCHFORD.
LEWIS D. EVANS.

In presence of—

O. W. ALDRICH,
C. C. SHEPHERD.
